DESIGN FOR A SPECTACLE FRAME

Abraham R. Grossman, Jackson Heights, N. Y.

Application August 28, 1942, Serial No. 108,060

Term of patent 14 years

To all who it may concern:

Be it known that I, Abraham R. Grossman, a citizen of the United States, residing at 30-12 89th Street, Jackson Heights, Long Island, county of Queens, and State of New York, have invented a new, original, and ornamental Design for Spectacle Frames, of which the following is a specification, reference being had to the accompanying drawing, forming part thereof.

Figure 1 is a front elevation of the front of a spectacle frame embracing this invention, and Figure 2 is a top plan view of the complete spectacle frame.

I claim:

The ornamental design for a spectacle frame, as shown.

ABRAHAM R. GROSSMAN.
